2,388,322

MANUFACTURE OF GASOLINE

Nelson B. Haskell, Port Arthur, Tex., assignor to
The Texas Company, New York, N. Y., a corporation of Delaware

Application January 15, 1943, Serial No. 472,432

7 Claims. (Cl. 196—8)

This invention relates to the manufacture of gasoline hydrocarbons of high antiknock value from light or normally gaseous hydrocarbons. More particularly, the invention relates to the stabilization and fractionation of light or normally gaseous hydrocarbon mixtures, and to the recovery of desired fractions from refinery gases, to provide suitable charges for further processing in the manufacture of the gasoline hydrocarbons.

One of the principal objects of the invention is to provide a novel method of stabilizing and fractionating light or normally gaseous hydrocarbon mixtures to effect an improved separation of desired fractions from undesired lighter and heavier hydrocarbons therein.

Another object of the invention is to provide an improved method of recovering from refinery gases, such as relief gases from a cracking operation, a desired sharply stabilized or close-cut fraction to furnish an improved charge to a catalytic or thermal conversion unit for the manufacture of gasoline hydrocarbons therefrom.

Still another object of the invention is to provide an improved method of depropanizing light or normally gaseous hydrocarbon mixtures, or absorption oil containing such absorbed hydrocarbon mixtures, to enable the recovery of C₄ or C₄ and heavier fractions which are substantially denuded of C₃ and lighter, while at the same time minimizing loss of desirable C₄ hydrocarbons.

Another object of the invention is to provide apparatus for carrying out the above methods, which apparatus is simple in construction, readily controlled, and economical in operation and maintenance.

Other objects and advantages of the invention will be apparent from the following description when taken in conjunction with the accompanying drawing and appended claims.

It is conventional refinery practice to recover condensable light or normally gaseous hydrocarbons, which are present in off-gases from various refinery operations such as cracking, by absorption of these gases in an absorption oil, followed by stripping of the absorbed hydrocarbons from the absorption oil. The resulting stripped gases are then further fractionated to separate fractions thereof, such as a C₄ fraction or C₃-C₄ fraction, for further processing as by alkylation, polymerization etc. to produce gasoline hydrocarbons of high antiknock value for aviation gasoline or motor fuel. In catalytic alkylation, it has been customary to separate a C₄ fraction from the rich absorption oil, which fraction contains the isobutane and the butylenes. In an endeavor to

conserve as much as possible of the available isobutane and lighter butylenes, such as isobutylene and butylene-1, the fractionation and stripping of the rich absorption oil has been conducted under conditions which retain a substantial proportion of propane in the recovered fraction charged to the alkylation unit. This propane is undesirable as constituting a diluent which raises the pressure required to maintain the charge in liquid phase, and necessitating the use of expensive and complicated alkylate fractionating equipment to prevent build-up of propane in the system while conserving isobutane for recycling to the alkylation unit. Where the preliminary fractionation is carried out under conditions to more completely eliminate propane from the charge, a substantial loss of isobutane and butylenes has resulted with the heretofore known processing and equipment.

In accordance with the present invention, an improved method and apparatus are provided whereby a more complete separation of undesired hydrocarbons, such as propane, is made from the desired fraction which is subjected to further processing for the manufacture of gasoline hydrocarbons. As applied to the recovery of hydrocarbons from refinery gases, this is accomplished by absorbing the gases in a conventional absorption oil, then prestabilizing the rich absorption oil to remove undesired lighter hydrocarbons, such as C₃ and lighter, stripping the resultant prestabilized rich absorption oil to recover absorbed hydrocarbons including those desired for further processing, and injecting into the prestabilizer a hydrocarbon stream which is heavier than the lighter hydrocarbons removed in the prestabilizing step and is substantially denuded of such lighter hydrocarbons. Preferably, this stream of injected hydrocarbons is obtained by recycling overhead condensate from the stripper.

As applied to the recovery of a C₄ fraction for alkylation, the rich absorption oil is first prestabilized preferably under high pressure to remove overhead C₃ and lighter, and the resulting depropanized rich absorption oil is then passed to a stripper preferably operating at reduced pressure, where a stream of C₄ and heavier is removed overhead, to provide a lean absorption oil bottoms for recycling to the absorption operation; and a portion of the overhead C₄ and heavier condensate from the stripper is recycled to the prestabilizer. The rich absorption oil may be preheated before being introduced into an intermediate portion of the prestabilizer, which latter is operated with the usual return of overhead condensate to the

upper portion thereof to serve as reflux; and the recycled condensate from the stripper is introduced into the prestabilizer below the point of introduction of the reflux condensate thereto. The recycled condensate may be mixed in whole or in part with the stream of rich absorption oil for introduction into the prestabilizer; or the recycled condensate may be introduced in whole or in part at one or more points of the prestabilizer above or below the point of introduction of the rich absorption oil. The relative points of entry of the rich absorption oil feed and the recycle condensate into the prestabilizer tower for best operation depend upon the average volatilities of the recycle stream and the absorbed hydrocarbons of the rich oil stream, with the stream having the higher average volatility being introduced above the other stream. The point of entry of the rich oil stream can be varied with advantage in accordance with the character of the equipment and the composition of the feed, as will be obvious to those skilled in the operation of stabilizer equipment.

A preferred embodiment of the invention is illustrated in the attached drawing, in which the single figure is a diagrammatic illustration of apparatus suitable for carrying out the method herein described.

Referring to the drawing, a wet refinery gas is introduced by line 10 into absorption tower 11 where it passes upwardly countercurrent to descending absorption oil introduced into the upper portion of the tower by the lean oil line 12. Unabsorbed dry gas is removed from the top of the tower by gas line 13 and passes to suitable gas accumulating lines for use as fuel or for other disposition. The absorption oil containing the absorbed hydrocarbons, including C₁-C₅ and a small amount of heavier hydrocarbons, is discharged from the base of tower 11 by line 14. This rich oil is forced by pump 15 through a suitable furnace heating coil 16 and thence introduced by line 17 into an intermediate portion of a prestabilizer tower 18. This tower may be operated at about 250-350 pounds per square inch gauge, with a heater outlet temperature of about 450-550° F., a bottom tower temperature of about 350-450° F., and a top tower temperature of about 100-140° F., to remove overhead C₃ and lighter by line 19. The overhead material is passed through a condenser 20 and thence by run-down line 21 to an accumulator 22, from which uncondensed gas is removed by relief line 23. Condensate is withdrawn from accumulator 22 by line 24 and forced in whole or part by pump 25 through line 26 to the top of prestabilizer 18 to serve as reflux therein.

A stream of depropanized rich oil is withdrawn from the base of tower 18 by line 28 and passed through a heating coil 32 and pressure reducing valve 29 into an intermediate portion of a stripper 30. The pressure is thereby reduced to about 40-100 pounds per square inch gauge; and this tower 30 may be operated with a bottom temperature of about 450-500° F. and a top temperature of about 125-175° F. to strip out and remove overhead through line 31 remaining absorbed hydrocarbons including C₄, C₅, and any heavier. It is to be understood that the above mentioned figures for pressure and temperature of the prestabilizer and stripper are given merely by way of example; and these figures can be altered substantially depending upon the particular charge and conditions of operation employed. While gas-fired heating coils 16 and 32 have been shown for heat-

ing the charges to the stabilizer and stripper respectively, it is to be understood that the towers may each be equipped with a gas-fired reboiler or other appropriate heating coil, which can be used in conjunction with the charge heating coil or in substitution therefor. Lean oil is discharged from the base of stripper 30 by line 33 and forced by pump 34 to line 12 for return to the absorption tower 11.

The overhead from stripper 30 passes through line 31 to condenser 36 and thence by run-down line 37 to accumulator 38, from which condensate is withdrawn by line 39. A portion of the condensate passes by line 40 to pump 41 which forces the latter in part through line 42 to the top of tower 30 to serve as reflux therein, and in part by recycle line 43 back to the prestabilizer 18. As shown, this recycled condensate can be introduced into line 17 and mixed with the preheated rich absorption oil for introduction into the tower; or it can be introduced directly into the tower 18 through one or more of branch lines 44, 45, and 46 at a point or points above or below, or both above and below the point of introduction of the rich oil to the tower. Again, a portion of the recycle condensate can be added to line 17, and another portion introduced through one of more of branch lines 44, 45, and 46. It is to be understood that the recycle condensate can be introduced into the prestabilizer at other points below the point of introduction of reflux from line 26.

Another portion of the condensate withdrawn from accumulator 38 by line 39 is passed by branch line 47 to pump 48 which forces the condensate to a fractionating tower or charge debutanizer 50. This tower is equipped with a suitable reboiler or heating coil 51 and may be operated at a pressure of 50-100 pounds per square inch gauge with a bottom temperature of about 180-280° F. and a top temperature of about 125-175° F. to remove overhead by line 52 a desired C₄ cut, and thereby separate the same from C₅ and heavier which is withdrawn as bottoms by line 53. The overhead is passed through condenser 54 and run-down line 55 to accumulator 56, from which condensate is withdrawn by line 57. The condensate is forced by pump 58 in part through line 59 to the top of tower 59 to serve as reflux therein, and in part through branch line 60, which may lead to a suitable conversion unit, such as an alkylation unit, where the C₄ hydrocarbons are reacted and converted into gasoline hydrocarbons of high antiknock value.

In continuous operation, there will be a buildup of the C₄-C₅ stripper condensate in the system to provide the necessary quantity for recycling through line 43, as well as to supply the requirements for stripper reflux through line 42, and eventually furnish sufficient charge passing through line 49 for further processing. The proportion of condensate recycled on the basis of the feed of rich oil to the prestabilizer can be varied within wide limits. Even a small proportion of recycle effects improved results as shown by a decrease in the propane content of the condensate. Ordinarily, the ratio by volume of recycled condensate to rich oil feed may vary between 1 part of recycle to 100 parts of rich oil feed up to about 1 part of recycle to 10 parts of rich oil feed; and preferably a ratio of around 1 part of recycle to around 20 parts of rich oil feed is employed.

While the use of the stripper condensate as the hydrocarbon stream which is injected into the prestabilizer provides a preferred operation, it is to be understood that any available C₄ stream

from an extraneous source can be employed. As shown, an available refinery C₄ stream, such as from the stabilization of cracked naphtha or natural gasoline, or from the stabilization and fractionation of gasolines produced by catalytic conversion, or from compressing cracking still gases, is introduced by pump 62 through line 63, which latter communicates with line 43. A portion of the injected hydrocarbon stream may be obtained by recycling stripper condensate, and another portion obtained from an external source through line 63.

By way of example, the following table sets forth data obtained in full scale plant operation of an absorption, prestabilizing and stripper assembly of the character described above, in the recovery from wet refinery gas and the preparation of a C₄ charge for a catalytic alkylation unit. While one absorption tower 11 has been shown in the drawing it will be understood that any number of absorption towers can be employed in parallel or series. In the runs listed below, three absorption towers were used in parallel, and the rich oil from the three towers was combined, prestabilized and stripped. The data set forth in the following four columns was obtained on four different days of operation of the same plant, utilizing different rates of stripper condensate recycle on the different respective days. The conditions of operation and the results obtained were as follows:

Table

	(1)	(2)	(3)	(4)
Prestabilizer:				
Tower pressure, lbs./sq. in. gauge.	310	310	310	310
Temperatures, ° F.:				
Charge to tower	408	413	380	368
Heater outlet	533	528	506	506
Tower bottom	404	400	369	361
Tower top	110	111	113	111
Accumulator	93	92	98	96
Rates, B. P. H.:				
Rich oil charge	1,683	1,701	1,701	1,703
Reflux	444	433	483	482
Stripper condensate recycle	0	30	75	81
Stripper:				
Tower pressure, lbs./sq. in. gauge.	70	69	69	69
Accumulator pressure, lbs./sq. in. gauge.	60	48	35	33
Temperatures, ° F.:				
Tower bottom	488	475	468	469
Tower top	160	160	163	163
Charge to tower	529	516	510	510
Accumulator	80	87	80	81
Rates, B. P. H.:				
Lean oil out	1,535	1,514	1,431	1,396
Stabilized condensate	131	134	129	128
Propane content of stabilized condensate, per cent	32.3	18.8	11.0	8.9

From the above, it will be noted that increasing the stripper condensate recycle rate from 0 to 81 barrels per hour with the rich oil feed rates shown resulted in a decrease in propane content of the stabilized condensate from approximately 32% to 9%. It is indicated that further increase in the ratio of recycle to rich oil feed would further reduce the propane content of the condensate. As the resulting condensate normally constitutes only a portion of the alkylation charge, other substantial portions being obtained from the stabilization of cracked naphtha and from fractionation of natural gasoline to supply additional isobutane, it will be appreciated that this invention enables the propane content of the charge to be reduced in a simple and economical manner to a very low figure while minimizing loss of desirable C₄ hydrocarbons.

While the invention has been described above as applied to the stabilization and fractionation of rich absorption oil, it is of course readily evi-

dent that the principles thereof are applicable to the stabilization and fractionation of light or normally gaseous hydrocarbon mixtures generally. Moreover, while the invention has been specifically described in connection with the depropanization and recovery of a C₄ fraction, it is to be understood that the invention is also applicable to the recovery of hydrocarbon fractions of different molecular weights. For example, a C₅ fraction can be recovered by prestabilizing to remove C₄ and lighter, and recycling to the prestabilizer a C₅ condensate. Likewise, a sharp separation between C₂ and C₃ may be effected by prestabilizing to remove C₂ and lighter and recycling to the prestabilizer a C₃ fraction.

Obviously many modifications and variations of the invention, as hereinbefore set forth, may be made without departing from the spirit and scope thereof, and therefore only such limitations should be imposed as are indicated in the appended claims.

I claim:

1. The method in the recovery of a desired C₄ fraction from refinery gases containing C₄ hydrocarbons and both heavier and lighter hydrocarbons than C₄, which comprises absorbing the refinery gases in a lean absorption oil, prestabilizing the resulting rich absorption oil to remove overhead C₃ and any lighter hydrocarbons, condensing a portion of said overhead C₃ and any lighter hydrocarbons and returning at least a part of the said condensate as reflux to an upper portion of the prestabilizing zone, stripping the prestabilized rich absorption oil to remove C₄ and substantially all heavier absorbed hydrocarbons to thereby recover a lean absorption oil, recycling said lean absorption oil to the absorption step, condensing at least a portion of the C₄ and heavier hydrocarbons removed by stripping, returning a portion of the C₄ and heavier condensate to the stripping step to serve as reflux therein, passing another portion of the C₄ and heavier condensate to a fractionating zone where the desired C₄ fraction is separated from heavier hydrocarbons, removing the desired C₄ fraction overhead from said fractionating zone and subjecting the same to condensation, returning a portion of the resulting condensate as reflux to an upper portion of said fractionating zone, discharging the balance of said condensate from the system as the recovered C₄ fraction, and injecting into the rich oil prestabilizing zone at an elevation substantially below the point of reflux return thereto a hydrocarbon stream heavier than the C₃ and any lighter hydrocarbons removed overhead therefrom, said stream being largely denuded of said C₃ and lighter hydrocarbons but containing a substantial proportion of the desired C₄ hydrocarbons, whereby a more complete separation of the undesired C₃ and any lighter hydrocarbons from the C₄ and heavier hydrocarbons is effected in the prestabilizing step while minimizing loss of desired C₄ hydrocarbons in the overhead from said step.
2. The method according to claim 1, wherein the rich absorption oil is preheated and introduced into an intermediate portion of a fractionating zone of the prestabilizing step, the reflux for that step is introduced into an upper portion of said zone, and the said injected hydrocarbon stream is first admixed at least in part with the preheated rich absorption oil and introduced therewith into said zone.
3. The method according to claim 1, wherein the rich absorption oil is introduced into an in-

termidiate portion of a fractionating zone of the prestabilizing step, the reflux for that step is introduced into an upper portion of said zone, and the said injected hydrocarbon stream is mixed in part with the rich absorption oil for introduction into said zone and introduced in part directly into said zone at a point below the point of introduction of said rich absorption oil.

4. The method according to claim 1, wherein the injected hydrocarbon stream comprises at least in part a portion of the C₄ and heavier overhead condensate from said stripping step.

5. The method in the recovery of a C₄-containing hydrocarbon fraction from refinery gases containing C₂-C₅ hydrocarbons, which comprises subjecting the refinery gases to treatment with an absorption oil, prestabilizing the resulting rich absorption oil to remove overhead absorbed C₃ and lighter, subjecting said overhead C₃ and lighter to cooling and condensation, returning at least a portion of the resulting condensate as reflux to an upper portion of the prestabilizing zone, stripping the prestabilized rich absorption oil to remove overhead C₄ and heavier and recover a lean absorption oil which is recycled to the absorption step, condensing at least a portion of said C₄ and heavier overhead from the stripping step, fractionating a portion of said stripper condensate to separate the desired C₄-containing hydrocarbon fraction overhead from heavier hydrocarbons removed as bottoms, diverting at least a portion of said last-mentioned overhead from the system as the recovered C₄-containing hydrocarbon fraction, and recycling another portion of the said stripper condensate to the prestabilizing step and introducing the same therein at a plurality of different elevations which are all below the point of reflux return to said prestabilizing zone.

6. The method in the recovery of a C₄ hydrocarbon fraction from refinery gases containing C₂-C₅ hydrocarbons, which comprises subjecting the refinery gases to treatment with an absorption oil, prestabilizing the resulting rich absorption oil to remove overhead absorbed C₃ and lighter subjecting said overhead C₃ and lighter to cooling and condensation, returning at least a portion of the resulting condensate as reflux to an

upper portion of said prestabilizing zone, stripping the prestabilized rich absorption oil to remove overhead a stream comprising mainly C₄ and C₅ hydrocarbons and recover a lean absorption oil which is recycled to the absorption step, subjecting said overhead stream to condensation to produce a C₄-C₅ condensate, recycling a portion of said C₄-C₅ condensate to said prestabilizing zone at an elevation below the point of reflux return thereto, fractionating another portion of said C₄-C₅ condensate to separate a C₄ fraction overhead from heavier hydrocarbons, condensing said overhead C₄ fraction and discharging at least a portion of said condensate as the recovered C₄ hydrocarbon fraction.

7. Apparatus of the character described comprising, in combination, an absorber, means for supplying hydrocarbon gases and an absorption oil to said absorber, a prestabilizer, means for supplying rich absorption oil from said absorber to said prestabilizer, means for heating said prestabilizer to remove lighter hydrocarbons therefrom including a heating coil for the hydrocarbon charge supplied thereto, a condenser and accumulator connected to the overhead line of said prestabilizer, a reflux pump and reflux line for returning condensate from said accumulator to an upper portion of said prestabilizer, a stripper, means for supplying prestabilized rich oil from said prestabilizer to said stripper including a pressure release valve for lowering the pressure on the hydrocarbons in said stripper, means for supplying heat to said stripper to remove remaining absorbed hydrocarbons from said rich oil, means for returning lean oil from said stripper to said absorber, a charge fractionator, means for supplying overhead hydrocarbons from said stripper to said charge fractionator, and means for recycling a portion of said overhead hydrocarbons from said stripper to said prestabilizer including a condenser for condensing at least a portion of said overhead and an accumulator for the condensate, a pump for supplying condensate at least at the prestabilizer pressure, and a line from said pump opening into said rich absorption oil supplying means between said heating coil and said prestabilizer.

NELSON B. HASKELL.
